UNITED STATES PATENT OFFICE.

JAMES CARTER, OF HUNTINGTON, WEST VIRGINIA.

METAL ROOF AND EAVES-TROUGH.

No. 872,646.

Specification of Letters Patent.

Patented Dec. 3, 1907.

Application filed January 16, 1907. Serial No. 352,568.

To all whom it may concern:

Be it known that I, JAMES CARTER, a citizen of the United States, residing at Huntington, in the county of Cabell and State of 5 West Virginia, have invented certain new and useful Improvements in Metal Roofs and Eaves-Troughs, of which the following is a specification.

This invention relates to roofing designed 10 most especially for railway cars although readily adaptable to dwellings and other structures to be protected from the weather.

The invention provides a novel joint between the roof sections, or plates, which will 15 effectually exclude dampness and admit of a certain amount of contraction and expansion due to climatic changes without resulting in opening of the joint.

A further purpose of the invention is the 20 construction of a sheet metal roofing which may be secured to the car structure without exposing the fastenings and which will admit of the fastenings being readily removed or loosened should it be required from any 25 cause to replace a section, or plate.

The invention also has for its object the provision of a sectional eaves trough which will adapt itself to either the camber or sheer of a roof so as to shed the water and prevent 30 running of the same upon the sides of the car, or other structure. The sections of the eaves trough have their ends overlapped and are adapted to be secured in place by means of concealed flanges and fastenings.

35 For a full description of the invention and the merits thereof and also to acquire a knowledge of the details of construction and the means for effecting the result, reference is to be had to the following description and 40 accompanying drawings.

While the invention may be adapted to different forms and conditions by changes in the structure and minor details without departing from the spirit or essential features thereof, still the preferred embodiment is shown in the accompanying drawings, in which:

Figure 1 is a perspective view of a portion of a car roof embodying the invention. Fig. 50 2 is a transverse section of the joint formed between adjacent plates, or roof sections on the line $x-x$ of Fig. 1 showing the part on a larger scale. Fig. 3 is a transverse section of the eaves trough, plate and roof section 55 on the line $y-y$ of Fig. 1. Fig. 4 is a detail perspective view of a roof section, or plate,

the same being inverted. Fig. 5 is a detail perspective view of an eaves trough section.

Corresponding and like parts are referred to in the following description and indicated 60 in all the views of the drawings by the same reference characters.

The invention is shown applied to a freight car, two of the eaves trough sections being oppositely inclined above the door-way to 65 shed the water to each side thereof as indicated most clearly in Fig. 1.

The roof sections, or plates 1 may be of any dimensions and are formed of sheet metal such as commonly employed for the 70 roofing of cars, sheds, or other structures. Each section or plate 1 is provided at its longitudinal edges with rolls 2 and 3. One of the rolls overlaps the section, or plate, whereas the opposite roll projects from said section, or plate, so as to overhang and match with the roll of the adjacent section, or plate. The rolls 2 and 3 are of like formation, the one being a trifle larger than the other so as to telescope therewith when the roof sections, or plates are in position. The roll 2 75 overhangs the section, or plate. The roll 3 projects from the section, or plate. Each roll in cross section is approximately of circular outline and terminates in a vertical, 80 or up-standing flange 4. The sections, or plates, are fitted together by slipping the roll 2 within the roll 3, the vertical, or up-standing flange 4 of the rolls coming close together and serving with the lower portion of the roll 90 to form a gutter to direct any moisture that may find its way in the roll outward and effectually excluding the entrance of any moisture to the sheeting or interior of the car, or other structure. The rolls 2 and 3 are of 95 such relative sizes as to obtain a close joint throughout their subjacent portions thereby preventing any moisture passing by the joint to the under side of the roof plates, or sections. The rolls 2 and 3 admit of contrac-

100 tion and expansion of the roof sections, or plates, without opening the joints, or causing the roof to buckle, or warp. The lower or outer ends of the roof sections, or plates 1, are rebent as indicated at 5 to underlap the 105 section, or plate, and are thence bent about at a right angle to form the vertical or securing flange 6 which in car structures extends along the inner side of the plate 7 to which the said vertical or securing flange 6 is attached. The fold formed by bending the outer end of the plate 1, admits of the latter 110

having a vibratory movement without straining or tending to loosen the metal roofing from the car.

The eaves trough is composed of a series of sections, each section consisting of a trough 8 and wings 9 and 10. The trough 8 inclines throughout its length and also has its bottom transversely inclined to direct the water towards the outer side, or wall of the trough, 10 to effect discharge of the water at a point remote from the side of the car. The inner wall, or side of the trough 8 gradually deepens to correspond to the inclination of the trough longitudinally. The wing 9 extends 15 over the plate 7 and comes beneath the bent end portion 5 of the roof plate, or section 1. The wing 10 lies against the inner side of the plate 7 and is secured thereto by nails, or other fastenings. The sections may 20 be of any length and are arranged with their ends overlapped so that all the water shed by the roof may be discharged into the eaves trough as a whole and delivered from the latter at points corresponding with the discharge 25 ends of the eaves trough sections.

From the foregoing, it will be understood that the roof sections, or plates 1, are interlocked at their longitudinal edges and are secured to the car, by fastenings which are concealed and which at the same time are readily accessible to be withdrawn should it be required to remove any section, or plate 1, for any purpose. The sections of the eaves trough are likewise attached to the car by 30 means of concealed and projected fastenings which may be removed at any time should it be required to replace any section of the eaves trough from any cause. The plates 11 are attached to the side of the car opposite to 35 the discharge of the eaves trough sections to direct any water outward that may tend to splash against the side of the car.

In the application of the invention to car

roofs, the roof sections, or plates, are of a length to extend from the ridge pole to the 45 eaves, the inner or upper ends of the roof plates upon opposite sides of the ridge pole overlapping slightly and being protected by the cap plate and by the running board, the latter being supported in the usual manner 50 by brackets. A finishing strip 12 may be attached to the plate 7 so as to cover the securing flanges 6 and vertical wings 10 of the roof plates and eaves trough sections.

Having thus described the invention, what 55 is claimed as new is:

1. Sheet metal roofing comprising plates, or sections, each plate or section having an end portion folded upon itself, thence bent outward about at a right angle to form a securing flange and provided at opposite longitudinal edges with matching rolls terminating in upstanding flanges, the rolls ending at the folded end of a plate and arranged upon the side thereof opposite to the securing 65 flange, the several plates being adapted to be fitted together by slipping the rolls one within the other.

2. In combination a sheet metal roof composed of sections, or plates, having matching 70 rolls which interlock by a slip joint, each plate having an end folded upon itself, thence bent about at a right angle, and a sectional eaves trough having a horizontal wing to underlap the folded portion of the plates and a 75 vertical wing to underlap the pendent portion of the roof plates, and fastenings passed through the overlapped vertical portions of the roof plates and eaves trough sections to secure them to the roof structure.

In testimony whereof I affix my signature in presence of two witnesses.

JAMES CARTER. [L. S.]
